UNITED STATES PATENT OFFICE

172,580

WALL ORNAMENT

Frederick C. Cain, Long Beach, Calif.

Application January 5, 1954, Serial No. 28,383

Term of patent 7 years

(Cl. D29—23)

To all whom it may concern:

Be it known that I, Frederick C. Cain, a citizen of the United States, residing at Long Beach, in the county of Los Angeles and State of California, have invented a new, original, and ornamental Design for a Wall Ornament, of which the following is a specification, reference being had to the accompanying drawing, forming part thereof.

I claim:

The ornamental design for a wall ornament, as shown.
